HAND GRENADE

Clarence H. Braun, Hicksville, N. Y.

Application May 18, 1942, Serial No. 443,357

13 Claims.

(Cl. 102—64)

This invention relates to new and useful improvements in a hand grenade.

The invention proposes a hand grenade which is characterized by a hollow body for the explosive material, a percussion cap seat mounted through the front end of said body over said percussion cap seat and adapted to discharge the hand grenade when it is thrown and strikes an object.

More particularly, the invention proposes that a casing be threadedly mounted on the front of the body over said cap seat so as to be removable and releasable, as desired, to give access to the cap seat so that a cap may be placed thereon. It is further proposed that the operating mechanism of the hand grenade be mounted on and in said casing.

More particularly, it is contemplated that a plunger shaft be slidably mounted in the said casing and be provided with a firing head aligned with said cap seat, that resilient means be provided for urging said plunger shaft towards said cap seat, and that a safety bolt, and catches be provided for controlling the plunger shaft in a certain way.

It is proposed that the safety bolt be transversely slidably mounted on the casing and normally engage a longitudinal slot in the plunger shaft for controlling the longitudinal distance through which the plunger shaft may move, and it is proposed that said slot terminate in an opening which when engaged by said safety bolt locks the plunger shaft in a cocked loaded position. In so far as the catches are concerned, it is proposed that they be mounted on the casing forwards of the safety bolt and be cooperative with elements on the plunger shaft for locking the same in a cocked loaded position.

It is also contemplated that a head for the grenade be slidably and non-rotatively mounted on the front end of the casing, and that it have a tubular shaft entering said casing and encircling said plunger shaft. Furthermore, it is proposed that the tubular shaft be so designed that when the head of the grenade is depressed, it engages and releases said catches.

Resilient means is also proposed for urging the head of the grenade outwards. Small latches are also provided on the tubular shaft of the grenade head and are coactable and engageable with elements on the plunger shaft for gripping the same to move the plunger shaft outwards to its cocked position, when the grenade head is pulled outwards.

For further comprehension of this invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a hand grenade constructed in accordance with this invention.

5. Fig. 2 is an enlarged fragmentary longitudinal sectional view of the hand grenade illustrated in a position in which the plunger shaft is not yet cocked.

Fig. 3 is a sectional view taken on the line 10 3—3 of Fig. 2.

Fig. 4 is a fragmentary enlarged detailed view of a portion of Fig. 2 showing particularly the details of one of the latches.

Fig. 5 is a sectional view similar to Fig. 2 but 15 illustrating the plunger shaft in its cocked position in which the hand grenade is ready to be thrown.

The hand grenade, in accordance with this invention, includes a hollow body 10 for the explosive charge 10' of the grenade. The handle 11 by which the grenade may be gripped and thrown is mounted upon one end of the hollow body 10. The other end of the hollow body is provided with a closure wall 12 which has a certain way.

20 central opening through which a percussion cap seat 13 is mounted. This percussion cap seat is supported on several webs 14 which connect with a ring 15 mounted in the end of the body 10. A casing 16 threadedly engages on the front end of the body 10 and over the cap seat 13 and engages the ring 15 for releasably holding the same in position.

25 A plunger shaft 17 is slidably mounted in the casing 16 and has a firing head 18 aligned with the said cap seat 13. Resilient means acts between the casing 16 and the plunger shaft 17 for urging it towards the cap seat 13. This resilient means comprises a spring 19 mounted within the casing 16 and acting between a partition 20 formed in the casing and a washer 21 which is engaged behind the firing head 18.

30 A safety bolt 22 is transversely slidably mounted on the casing 16 and engages a longitudinal slot 23 on the plunger shaft 17. This slot 23 connects at one end with a transverse opening 24 through the plunger shaft 17. When the plunger shaft 17 is in its cocked loaded position, the opening 24 will be aligned with and engaged by the safety bolt 22.

35 The safety bolt 22 is urged inwards by a spring 25 acting between a flange 26 on the bolt and a side portion of the casing 16. The safety bolt is provided with a laterally projecting pin 27 engaging a slot 28 in the casing 16. The safety bolt 22 may be manually gripped and pulled 40 outwards and turned to disengage the pin 27 from the slot 28, and then it will be retracted out of contact with the plunger shaft 17 which is then free and may act in a certain way, as 45 hereinafter more fully described.

Catches 30 are mounted on the casing 16 and are cooperative with complementary elements, such as a groove 31 on the plunger shaft 17 for locking the latter in its cocked loaded position. In Fig. 2 the catches 30 are shown inoperative. In Fig. 5 the catches 30 are shown engaging the groove 31 for locking the plunger shaft, as stated. The catches 30 comprise springs mounted at one of their ends on the casing 16 and arranged so that their other ends normally tend to engage the groove 31. While springs have been shown for this purpose it should be borne in mind that other types of catches may be used, depending merely on design.

A head 33 for the grenade is slidably and non-rotatively mounted on the front end of the casing 16. The head 33 has a projecting pin 34 which engages a longitudinally extended slot 35 on the casing 16 to prevent the head from turning. The head 33 is provided with a central projecting tubular shaft 36 which enters the casing 16 and which encircles one end of the plunger shaft 17. The tubular shaft 36 normally does not engage the catches 30, as illustrated in Fig. 5. However, when the grenade head 33 is pressed inwards, the inner end of the tubular shaft 36 engages the catches 30, spreading them and moving them to inoperative positions so that they are free from the plunger shaft 17.

Resilient means urges the head 33 outwards. This resilient means comprises a helical spring 37 mounted on the tubular shaft 36 and acting between a shoulder 38 formed in the casing 16, and a portion of the head 33 for normally urging the head outwards. Latches 39 are mounted upon the tubular shaft 36 and are engageable with elements 40 on the plunger shaft 17 for gripping the same so that the plunger shaft may be moved to its cocked loaded position when the head 33 is pulled slightly outwards. Each of the catches 39 comprises a lever member 41 having one end mounted in an opening in the side of the tubular shaft 36 and pivotally supported at this point by a pintle 42. A stem 43 pivotally connects with an intermediate point of each lever member 41 and extends outwards through an opening 44 in the side of the tubular shaft 36. Each stem 43 is provided with a head 45 which limits its inward motion. A ball socket 46 is slidably mounted on each stem 43. An expansion spring 47 is coaxially mounted on each stem 43 and acts between the ball socket 46 and the side of the lever member 41 for urging the arm inwards. The elements 40 comprise longitudinally extending grooves formed in the side of the plunger shaft 17.

Each of the lever members 41 is formed with a curved tail 48 which extends along the outer face of the tubular shaft 36 when the ends of the lever members are engaged within the grooves 40. The interior of the casing 16 is formed with inwardly extending projections 49 which extend into the path traversed by the tails 48 when the head 33 and plunger 17 moves from the cocked position shown in Fig. 5 to the position in which the firing head 18 strikes the percussion cap in the cap seat 13 to set off the grenade. At a point during this movement, and more particularly when the firing head is about in position to hit the cap, the tails 48 will ride beneath the projections and pivot the lever members and disengage the lever members 41 from the grooves. This movement will free the plunger of the head 33 and permit the spring 47 to urge the plunger the remaining distance and cause the firing head 18

to hit the cap with sufficient force to cause the grenade to be exploded.

An auxiliary means is provided for assisting in maintaining the head 33 in its inoperative position as shown in Fig. 2. This means comprises a pair of bolts 50 mounted within the casing 16 and arranged to be cooperative with opposite sides of the tubular shaft 36 of the head 33. Each of these bolts 50 is alike in construction and explicit details of their construction is given in Fig. 4. Each bolt 50 comprises a stud shaft 51 slidably mounted in a recess 52 formed with the casing 16. A ball member 53 is mounted on the inner end of the stud shaft 51 and is cooperative with a complementary recess 54 formed in the side of the tubular shaft 36. The recess 54 has curved side walls to permit the ball member 53 to freely ride in and out of the recess when the head is forced in one direction or the other.

Resilient means is provided for urging the stud shaft 51 to cause the ball member 53 to bear constantly against the side of the tubular shaft 36. This means comprises an expansion spring 55 coaxially mounted upon an intermediate portion of the stud shaft 51. The spring 55 operates between the base wall of the recess 52 and a collar 56 mounted on the inner end of the stud shaft 51 to retain the ball member 53 in facial contact with the side of the tubular shaft 36.

The operation of the hand grenade may be understood from the following:

The hand grenade is supplied with the head 33 removed and with the safety bolt 22 engaging the longitudinal slot 23 of the plunger shaft 17. The casing 16 is turned to threadedly disconnect it from the hollow body 10. A percussion cap is then placed on the percussion cap seat 13. The hollow body 10 is supplied containing the explosive charge 10'. The casing 16 is then screwed back on the body 10. The firing head 18 will be held about $\frac{1}{8}$ inch away from the percussion cap and held by the safety bolt 22.

The head 33 is then slipped on the casing 16 and moved until the latches 39 slide up over the end of the plunger shaft 17 and then engage into the longitudinal slots 40. The parts are shown in this condition in Fig. 2.

The hand grenade is cocked by pulling the head 33 slightly rearwards. Since the lever members 41 are engaging the outer ends of the slots 40 they will pull the plunger shaft 17 to its cocked position. In this position the catches 30 will engage the groove element 31, and simultaneously the bolt 22 will engage the opening 24. The parts are shown in this condition in Fig. 5.

In the cocked position of the hand grenade the spring 47 is under compression ready to shoot the plunger shaft 17 forwards so that its firing head strikes the percussion cap. When one desires to throw the hand grenade it is necessary that the safety bolt 22 be pulled outwards so that it disengages from the opening 24. Then it must be slightly turned so that the pin 21 engages the outside of the casing 16 which holds the safety bolt 22 inoperative. The catches 30 are now holding the plunger shaft 17 in its cocked position. When the grenade is thrown and strikes an object the head 33 will be pressed inwards. As the head 33 moves inwards the plunger 17 will also move inwards therewith. This inward motion as a result will continue until the tail members 48 of the catches 30 engage beneath the projections 49. This will cause the free ends of the lever members 41 to be pivoted in a clockwise direction to disengage the ends of the lever members 41 from

the grooves 40. By this time the free end of the tubular shaft will have engaged the springs 39 and moved to a position similar to that shown in Fig. 2. This will free the plunger of the tubular shaft 36 and the casing 16 to be continued on its way towards the cap by the spring 19. The spring 19 instantly shoots the plunger shaft 17 forwards so that the firing head 18 strikes the percussion cap. This sets off the hand grenade.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Patents is:

1. A hand grenade, comprising an explosive material and a hollow body therefor, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in an opening which engaged by said bolt locks the plunger shaft in a cocked loaded position, catches on said casing and forwards of said safety bolt, elements on said plunger shaft to be engaged by said catches for locking the same in a cocked loaded position, a head for the grenade slidably and non-rotatively mounted on the front end of said casing and having a tubular shaft entering said casing and encircling said plunger shaft, and when depressed engaging and releasing said catches, resilient means urging said head outwards, latches mounted on said tubular shaft and elements on said plunger shaft to be engaged by said latches for gripping same to move said plunger shaft to its "cocked" position when said head is pulled slightly outwards.

2. A hand grenade, comprising an explosive material and a hollow body therefor, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in an opening which when engaged by said bolt locks the plunger shaft in a cocked loaded position, catches on said casing and forwards of said safety bolt, elements on said plunger shaft to be engaged by said catches for locking the same in a cocked loaded position, a head for the grenade slidably and non-rotatively mounted on the front end of said casing and having a tubular shaft entering said casing and encircling said plunger shaft, and when depressed engaging and releasing said catches, resilient means urging said head outwards, latches mounted on said tubular shaft, and elements on said plunger shaft to be engaged by said latches for gripping same to move said plunger shaft to its "cocked" position when said head is pulled slightly outwards, said hollow body being provided

with a handle by which the grenade may be gripped, handled, and thrown.

3. A hand grenade, comprising an explosive material and a hollow body therefor, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in an opening which when engaged by said bolt locks the plunger shaft in a cocked loaded position, catches on said casing and forwards of said safety bolt, elements on said plunger shaft to be engaged by said catches for locking the same in a cocked loaded position, a head for the grenade slidably and non-rotatively mounted on the front end of said casing and having a tubular shaft entering said casing and encircling said plunger shaft, and when depressed engaging and releasing said catches, resilient means urging said head outwards, latches mounted on said tubular shaft, and elements on said plunger shaft to be engaged by said latches for gripping same to move said plunger shaft to its "cocked" position when said head is pulled slightly outwards, said resilient means for urging the plunger shaft forwards comprising a washer behind the firing head of the plunger shaft, and an expansion spring acting between said casing and said washer.

4. A hand grenade, comprising an explosive material and a hollow body therefor, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in an opening which when engaged by said bolt locks the plunger shaft in a cocked loaded position, catches on said casing and forwards of said safety bolt, elements on said plunger shaft to be engaged by said catches for locking the same in a cocked loaded position, a head for the grenade slidably and non-rotatively mounted on the front end of said casing and having a tubular shaft entering said casing and encircling said plunger shaft, and when depressed engaging and releasing said catches, resilient means urging said head outwards, latches mounted on said tubular shaft, and elements on said plunger shaft to be engaged by said latches for gripping same to move said plunger shaft to its "cocked" position when said head is pulled slightly outwards, said safety bolt being provided with a projecting pin engaging a slot in said casing whereby the bolt may be pulled outwards until the pin disengages the slot and then the bolt may be turned to engage said pin against the outside of said casing for holding the safety bolt inoperative.

5. A hand grenade comprising an explosive material and a hollow body therefor, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger

shaft for urging it towards said cap seat, a safety bolt transversely slidably mounted on said casing and engaging a longitudinal slot on said plunger shaft, said slot terminating in an opening which when engaged by said bolt locks the plunger shaft in a cocked loaded position, catches on said casing and forwards of said safety bolt, elements on said plunger shaft to be engaged by said catches for locking the same in a cocked loaded position, a head for the grenade slidably and non-rotatively mounted on the front end of said casing and having a tubular shaft entering said casing and encircling said plunger shaft, and when depressed engaging and releasing said catches, resilient means urging said head outwards, latches mounted on said tubular shaft, and elements on said plunger shaft to be engaged by said latches for gripping same to move said plunger shaft to its "cocked" position when said head is pulled slightly outwards, said catches comprising leaf springs mounted on the casing and having free ends urged against said plunger shaft, and said elements on the plunger shaft for the catches comprising a groove formed in the plunger shaft.

6. A hand grenade comprising an explosive material and a hollow body therefor, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in an opening which when engaged by said bolt locks the plunger shaft in a cocked loaded position, catches on said casing and forwards of said safety bolt, elements on said plunger shaft to be engaged by said catches for locking the same in a cocked loaded position, a head for the grenade slidably and non-rotatively mounted on the front end of said casing and having a tubular shaft entering said casing and encircling said plunger shaft, and when depressed engaging and releasing said catches, resilient means urging said head outwards, latches mounted on said tubular shaft, and elements on said plunger shaft to be engaged by said latches for gripping same to move said plunger shaft to its "cocked" position when said head is pulled slightly outwards, said catches comprising leaf springs mounted on the casing and having free ends urged against said plunger shaft.

7. A hand grenade comprising an explosive material and a hollow body therefor, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in an opening which when engaged by said bolt locks the plunger shaft in a cocked loaded position, catches on said casing and forwards of said safety bolt, elements on said plunger shaft to be engaged by said catches for locking the same in a cocked loaded position, a head for the grenade

5 slidably and non-rotatively mounted on the front end of said casing and having a tubular shaft entering said casing and encircling said plunger shaft, and when depressed engaging and releasing said catches, resilient means urging said head outwards, latches mounted on said tubular shaft, and elements on said plunger shaft to be engaged by said latches for gripping same to move said plunger shaft to its "cocked" position when said head is pulled slightly outwards, said catches comprising leaf springs mounted on the casing and having free ends urged against said plunger shaft, and said elements on the plunger shaft for the catches comprising a groove formed in the plunger shaft.

8. A hand grenade comprising an explosive material and a hollow body therefor, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in an opening which when engaged by said bolt locks the plunger shaft in a cocked loaded position, catches on said casing and forwards of said safety bolt, elements on said plunger shaft to be engaged by said catches for locking the same in a cocked loaded position, a head for the grenade slidably and non-rotatively mounted on the front end of said casing and having a tubular shaft entering said casing and encircling said plunger shaft, and when depressed engaging and releasing said catches, resilient means urging said head outwards, latches mounted on said tubular shaft, and elements on said plunger shaft to be engaged by said latches for gripping same to move said plunger shaft to its "cocked" position when said head is pulled slightly outwards, said head having a projecting pin engaging a slot in said casing for accomplishing said non-rotative mounting of the head.

9. A hand grenade comprising an explosive material and a hollow body therefor, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in an opening which when engaged by said bolt locks the plunger shaft in a cocked loaded position, catches on said casing and forwards of said safety bolt, elements on said plunger shaft to be engaged by said catches for locking the same in a cocked loaded position, a head for the grenade slidably and non-rotatively mounted on the front end of said casing and having a tubular shaft entering said casing and encircling said plunger shaft, and when depressed engaging and releasing said catches, resilient means urging said head outwards, latches mounted on said tubular shaft and elements on said plunger shaft to be engaged by said latches for gripping same to move said plunger shaft to its "cocked" position when said head is pulled slightly outwards, said head having a projecting pin engaging a slot in

said casing for accomplishing said non-rotative mounting of the head, said resilient means for urging the head outwards comprising a spring mounted on said tubular shaft and acting between a shoulder on said casing and said head.

10. A hand grenade comprising an explosive material and a hollow body therefor, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in an opening which when engaged by said bolt locks the plunger shaft in a cocked loaded position, catches on said casing and forwards of said safety bolt, elements on said plunger shaft to be engaged by said catches for locking the same in a cocked loaded position, a head for the grenade slidably and non-rotatively mounted on the front end of casing and having a tubular shaft entering said casing and encircling said plunger shaft, and when depressed engaging and releasing said catches, resilient means urging said head outwards, latches mounted on said tubular shaft, and elements on said plunger shaft to be engaged by said latches for gripping same to move said plunger shaft to its "cocked" position when said head is pulled slightly outwards, said latches comprising angle members mounted through said tubular shaft, stems pivotally connected with the inner arms of the angle members, said stems being extended through the tubular shaft, and springs on said stems urging them inwards.

11. A hand grenade, comprising an explosive material and a hollow body therefor, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in opening which when engaged by said bolt locks the plunger shaft in a cocked loaded position, catches on said casing and forwards of said safety bolt, elements on said plunger shaft to be engaged by said catches for locking the same in a cocked loaded position, a head for the grenade slidably and non-rotatively mounted on the front end of said casing and having a tubular shaft entering said casing and encircling said plunger shaft, and when depressed engaging and releasing said catches, resilient means urging said head outwards, latches mounted on said tubular shaft, and elements on said plunger shaft to be engaged by said latches for gripping same to move said plunger shaft to its "cocked" position when said head is pulled slightly outwards, said latches comprising angle members mounted through said tubular shaft, stems pivotally connected with the inner arms of the angle members, said stems being extended through the tubular shaft, and springs on said stems urging them inwards, said elements for the latches comprising longitudinal grooves on said plunger shaft.

12. A hand grenade comprising an explosive material and a hollow body therefor, a percussion

cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in an opening which when engaged by said bolt locks the plunger shaft in a cocked loaded position, catches on said casing and forwards of said safety bolt, elements on said plunger shaft to be engaged by said catches for locking the same in a cocked loaded position, a head for the grenade slidably and non-rotatively mounted on the front end of said casing and having a tubular shaft entering said casing and encircling said plunger shaft, and when depressed engaging and releasing said catches, resilient means urging said head outwards, latches mounted on said tubular shaft, and elements on said plunger shaft to be engaged by said latches for gripping same to move said plunger shaft to its "cocked" position when said head is pulled slightly outwards, said head having a projecting pin engaging a slot in said casing for accomplishing said non-rotative mounting of the head, said resilient means for urging the head outwards comprising a spring mounted on said tubular shaft and acting between a shoulder on said casing and said head, and means for holding said head in an inward position against the action of the spring which tends to urge said head outwards.

13. A hand grenade comprising a hollow body for the explosive material of the grenade, a percussion cap seat mounted through the front end of said body, a casing threadedly mounted on the front of said body and over said cap seat, a plunger shaft slidably mounted in said casing and having a firing head aligned with said cap seat, resilient means acting between said casing and plunger shaft for urging it towards said cap seat, a safety bolt transversely slidably mounted on said casing and engaging a longitudinal slot on said plunger shaft, said slot terminating in an opening which when engaged by said bolt locks the plunger shaft in a cocked loaded position, catches on said casing and forwards of said safety bolt and cooperative with elements on said plunger shaft for locking the same in a cocked loaded position, a head for the grenade slidably and non-rotatively mounted on the front end of said casing and having a tubular shaft entering said casing and encircling said plunger shaft, and when depressed engaging and releasing said catches, resilient means urging said head outwards, and latches mounted on said tubular shaft and engageable with elements on said plunger shaft for gripping same to move said plunger shaft to its "cocked" position when said head is pulled slightly outwards, said head having a projecting pin engaging a slot in said casing for accomplishing said non-rotative mounting of the head, said resilient means for urging the head outwards comprising a spring mounted on said tubular shaft and acting between a shoulder on said casing and said head, and means for holding said head in an inward position against the action of the spring which tends to urge said head outwards, comprising spring pressed ball members engageable in a complementary recess formed in the sides of said tubular shaft.

CLARENCE H. BRAUN.
